DESIGN FOR A ROCKING CHAIR

Wolfgang Hoffmann, Batavia, Ill., assignor to
The Howell Company, St. Charles, Ill., a corpo-
ration of Illinois

Application August 15, 1936, Serial No. 64,420

Term of patent 3½ years

To all whom it may concern:

Be it known that I, Wolfgang Hoffmann, a citizen of the Republic of Austria, residing at Batavia, in the county of Kane and State of Illinois, have invented a new, original, and ornamental Design for a Rocking Chair, of which the following is a specification, reference being had to the accompanying drawing, forming a part thereof.

Figure 1 is a perspective view of a rocking chair, showing my new design; and

Fig. 2 is a side elevation thereof.

The dominant feature of the design consists in the frame of the rocking chair, shown in full lines.

I claim:

The ornamental design for a rocking chair, as shown and described.

WOLFGANG HOFFMANN.
